UNITED STATES PATENT OFFICE.

GEORGE P. WIGGINTON, OF KALAMAZOO, MICHIGAN, ASSIGNOR TO KALAMAZOO LOOSE LEAF BINDER CO., OF KALAMAZOO, MICHIGAN.

TEMPORARY BINDER.

1,227,718.

Specification of Letters Patent. Patented May 29, 1917.

Application filed February 10, 1916. Serial No. 77,494.

To all whom it may concern:

Be it known that I, GEORGE P. WIGGINTON, a citizen of the United States, residing at the city of Kalamazoo, county of Kalamazoo, State of Michigan, have invented certain new and useful Improvements in Temporary Binders, of which the following is a specification.

This invention relates to improvements in temporary binders.

My present improvements are particularly designed by me for embodiment in binders of the type shown in Letters Patent No. 1,010,556, issued to me December 5, 1911, and are an adaptation and, in some respects, an improvement upon the structure there illustrated.

The main objects of this invention are:

First, to provide in a temporary binder or loose sheet holder an improved adjusting mechanism.

Second, to provide an improved temporary binder or loose sheet holder which is capable of rapid manipulation to permit the removal or insertion of the leaves and one in which the mechanism is compact and simple.

Further objects, and objects relating to structural details, will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawing, forming a part of this specification, in which:

Figure I is a detail inside plan view of a structure embodying the features of my invention.

Fig. II is an enlarged inverted detail of the adjusting mechanism.

Fig. III is a side view of the adjusting key.

Fig. IV is a side view of the releasing key.

Fig. V is a detail inside plan view of a modified form of my invention.

Fig. VI is a detail inside view of the adjusting mechanism of the embodiment shown in Fig. V.

In the drawing similar reference characters refer to similar parts throughout the several views.

Referring to the drawing, the covers 1 and 2 are of any suitable structure, the cover 2

being provided with a chamber or recess 3 for the adjusting mechanism. The binding members 4 are preferably in the form of flexible strips and extend between the covers, being connected to the cover 1 at 5 and to the cover 2 through the adjusting mechanism.

The adjusting member 6 for the binding members is slidably mounted upon the rack bar 7 which is disposed longitudinally of the cover 2. These parts are in general the same as in my patent before referred to. The adjusting member 6 is secured in its adjusted position upon the bar 7 by means of the pawl 8 pivotally mounted at 9 on the inner side of the adjusting member. This pawl is held yieldingly in its operative position by means of the U-shaped spring 10, one arm of which is mounted on the pin 11 so that its free arm engages the pawl. The spring is also arranged so that it supports the pawl in inoperative position against the stop 12. See the dotted lines in Fig. II.

The pawl is shifted to and from its operative position by means of the key 13 having a bit 14 adapted to engage between the tangs 15 on the pawl.

The adjusting member 6 is provided with a key opening 16 for the key 13. The key is provided with an arm 17 which rides upon the top of the member 6 supporting it for rotative movement in the opening 16.

The adjusting key 18 is provided with pinion teeth 19 adapted to coact with the teeth of the bar. The adjusting member 6 has an opening 20 adapted to receive the key 18 and support it with its teeth or pinion in rotative engagement with the rack so that the rack may be adjusted by means of the key, the key, in effect, constituting an adjusting pinion.

The pawl, as stated, holds the parts in their adjusted position, but when released, as by means of the key, the adjusting member slides freely on the bar.

By this arrangement of parts, the binder may be quickly adjusted to extend or retract the binding members and when the binder is locked or the binding members are under stress they cannot be released except by means of the key or its equivalent, which is effective in preventing accidental releasing of the same or ordinary unauthorized manipulation.

The key opening 16 may, if desired, be

sealed, so that the binder cannot be opened without its becoming known.

In the modification shown in Figs. V and VI the binding strips are connected to an 5 adjusting member or cross bar 21 having a rack bar 22 connected thereto. This bar slides through the cross piece 23 mounted on the cover.

The adjusting means and the means for 10 retaining the parts in their adjusted position are the same as those described in Figs. I—IV.

I have not attempted to illustrate or describe certain other modifications and adaptations of my improvements which might be 15 desirable for certain conditions or adaptations, as I believe the disclosure made will enable those skilled in the art to which my invention relates to embody or adapt the 20 same as conditions or taste may require.

Having thus described my invention what I claim as new and desire to secure by Letters Patent, is:

1. In a temporary binder, the combination of a binding member, a rack bar, an 25 adjusting member for said binding member slidably mounted on said bar, a pawl mounted on the inner side of said adjusting member to coact with said bar, a spring 30 adapted to hold said pawl yieldingly in its operative and inoperative positions, a stop for said pawl when in inoperative position, and a key for adjusting said pawl to its operative and inoperative positions, 35 said adjusting member having an opening therein for said key.

2. In a temporary binder, the combination of a binding member, a rack bar, an 40 adjusting member for said binding member slidably mounted on said bar, a pawl mounted on the inner side of said adjusting member to coact with said bar, a spring 45 adapted to hold said pawl yieldingly in its operative and inoperative positions, and a key for adjusting said pawl to its operative and inoperative positions, said adjusting member having an opening therein for said key.

3. In a temporary binder, the combination 50 of a binding member, a rack bar, an adjusting member for said binding member slidably mounted on said bar, a pawl mounted on the inner side of said adjusting member to coact with said bar, a spring 55 adapted to hold said pawl yieldingly in its operative position, a key for adjusting said pawl to its operative and inoperative positions, said adjusting member having an opening therein for said key, and an 60 adjusting key provided with pinion teeth adapted to coact with the teeth of said rack, said adjusting member being provided with an opening positioned to support said key in rotative engagement with 65 said rack.

4. In a temporary binder, the combination of a binding member, a rack bar, an 70 adjusting member for said binding member slidably mounted on said bar, a pawl for retaining said adjusting member in its 75 adjusted positions on said bar, mounted on the inner side of said adjusting member, a removable key for releasing said pawl, and an adjusting key provided with pinion teeth adapted to coact with the teeth 80 of said rack, said adjusting member being provided with an opening positioned to support said key in rotative engagement with said rack.

5. In a temporary binder, the combination 85 of a binding member, a rack bar, an adjusting member for said binding member slidably mounted on said bar, means for retaining said adjusting member in its 90 adjusted positions on said bar, and a removable adjusting pinion adapted to coact with the teeth of said rack, said adjusting member being provided with an opening through which said adjusting pinion may be inserted and removed positioned to support 95 said pinion in rotative engagement with said rack.

6. In a temporary binder, the combination 100 of a binding member, a rack bar, an adjusting member for said binding member, means coacting with said bar for retaining said adjusting member in its 105 adjusted positions, a removable key for releasing said retaining means, and an adjusting pinion adapted to coact with the 110 teeth of said rack bar, said adjusting member being provided with an opening positioned to support said pinion in rotative engagement with said rack.

7. In a temporary binder, the combination 115 of a binding member, a rack bar, an adjusting member for said binding member, means coacting with said bar for retaining said adjusting member in its 120 adjusted positions, and a removable adjusting pinion adapted to coact with the teeth of said rack bar, said adjusting member being provided with an opening through which said adjusting pinion may be inserted and removed positioned to support 125 said pinion in rotative engagement with said rack.

8. In a temporary binder, the combination 130 with the covers and a binding member, of an adjusting means comprising a rack bar, and a removable key provided with pinion teeth adapted to coact with the teeth of said rack.

9. In a temporary binder, the combination 135 of a binding member, a rack bar, an adjusting member for said binding member slidably mounted on said bar, a pawl for retaining said adjusting member in its adjusted positions on said bar, mounted on the inner side of said adjusting member, a 140

removable key for releasing said pawl, and a removable adjusting key adapted to coact with the teeth of said rack bar.

10. In a temporary binder, the combination of a binding member, a rack bar, an adjusting member for said binding member slidably mounted on said bar, a pawl for retaining said adjusting member in its adjusted positions on said bar, and a re-

movable adjusting key adapted to coact 10 with the teeth of said rack bar.

In witness whereof I have hereunto set my hand and seal in the presence of two witnesses.

GEORGE P. WIGGINGTON. [L. S.]
